UNITED STATES PATENT OFFICE.

ERNESTO D. REYES, OF SAN JUAN, TERRITORY OF PORTO RICO.

COMBINATION ENTRY FORM FOR GAMES OR CONTESTS.

Application filed December 8, 1922. Serial No. 605,566.

To all whom it may concern:

Be it known that I, ERNESTO D. REYES, a citizen of the United States, and resident of San Juan, in the Territory of Porto Rico, have invented certain new and useful Improvements in Combination Entry Forms for Games or Contests, of which the following is a specification.

The invention relates to a combination entry form for games or contests. It relates particularly to an improved and novel form on which may be recorded various combinations of selections as winners in various contests which are to take place, the form being arranged to facilitate and simplify the recording of the selections and the calculation and recording of the number of combinations of winners in the various contests from among the recorded entries of selections as possible winners.

The improved form is an adjunct to the playing of what is in effect a game of pre-selection, or guessing, of the winners in future contests. If a series of foot races or horse races are to be held, for example, the players in the game of preselection endeavor to choose the winners in all the races. The player who guesses the greatest number of winners in the races wins the game.

In such game, the various players may each have as many guesses as desired at the list of winners in the series of contests to be held, account being taken of the number of guesses, or total number of combinations of the entries in each contest selected by the player as possible winners in such contest. With a series of six or seven contests to be held and say five or six contestants in each, the possible combinations of winners in all the contests will amount to many thousands.

It has previously been the custom for the players to record on a separate slip each combination of winners selected for a series of contests to be held. Thus to "play," say, one hundred combinations of winners in six contests would require the writing of six names of contestants on each of one hundred slips, or six hundred names. If the slips or sheets are to be made out in duplicate or triplicate, the labor involved is proportionately more.

In accordance with my invention this difficulty is overcome, and any desired number of combinations of winners may be recorded, in a very simple manner, on a single sheet, from which the total of combinations

"played" may be readily calculated and recorded on the sheet.

The invention, generally speaking, comprises the provision of a sheet or form so arranged, having such a physical structure and combination of spaces and designating words or other indicia, as to enable the results referred to to be achieved.

The objects of the invention consist in the provision of an improved form or sheet of the character and for the purposes referred to. Other objects will appear more fully hereinafter in the following specification and be particularly pointed out in the appended claims.

In order that the invention may be more clearly understood attention is hereby directed to the accompanying drawing forming part of this application and illustrating one embodiment of the invention. In the drawing the figure is a top plan view of a form or sheet comprising the invention.

Referring to the drawing, the sheet 1 is preferably made out in duplicate or triplicate, a sheet made out in triplicate being shown in the drawing, comprising the top portion 1^a, a portion 1^b folded under the same, and a portion 1^c under that. Portion 1^b is folded over portion 1^c along a perforated line 2^a. Portion 1^a may be folded along a perforated line (not shown) at the top edge of this portion indicated at 2^b which divides portion 1^a from portion 1^c. When entries are written on the top portion 1^a the same will be duplicated on portions 1^b and 1^c as by providing a suitable duplicating composition on the under sides of portions 1^a and 1^b. Such coating is indicated at 3^a and 3^b in the drawing, corner portions of portions 1^a and 1^b of the sheet being shown as turned over in order that the coating referred to may be shown.

Description of the portion 1^a only need be given since the underlying portions 1^b and 1^c are duplicates of portion 1^a. Portion 1^a is provided with a plurality of contest spaces such as the columns 4^a, 4^b, 4^c, etc., seven such spaces or columns being indicated in the drawing corresponding to seven races, or other contests which are to take place. These contest spaces or columns are designated by suitable words or indicia such as the words "First contest," "Second contest," "Third contest," etc., at the heads of the columns.

Space is provided within each of the con-

test spaces for the recording of the names of a plurality of intending contestants in such contests. Thus in the form shown in the drawing each of the contest columns is 5 divided by horizontal lines 5 into spaces in which various names may be written, numerals such as the numerals 1 to 7 indicated at the left of the sheet in the drawing, between the various horizontal lines, 10 preferably being provided to indicate the number of contestants.

A player may select only one list of winners in the contests to be held in which case he writes one name in each of the 15 contest spaces or columns 4^a, 4^b, etc. Thus he may regard as his judgment of the probable winners in the seven contests, the horses or other contestants indicated in the drawing in the first horizontal space as Almoner, 20 Ada M., Mabel, Jack, U. S., France and Prince.

Or he may wish to preselect various combinations of possible winners. A second combination would be made by substituting 25 Bob for Almoner in the first contest while leaving the entries in the other contests the same as the combination first indicated. Under the method previously used a second form would have had to be written out in 30 which the name Bob was given for the first contest and the names Ada M., Mabel, etc., previously referred to, written for his choices in the second and ensuing contests. In accordance with my invention all such 35 data is recorded on the one sheet.

Thus in the form shown in the drawing both Almoner and Bob are recorded for the first contest, both Jack and Jule for the fourth, and both France and Bettina for the 40 sixth. With entries so recorded the player has selected eight different combinations of contestants as may be seen by calculation. Thus in one combination Jule in the fourth contest is selected with all of the entries in 45 the first line of the blank other than Jack, in another combination Jule is selected in the fourth contest with all of the entries in the first line of the other contest columns except the first contest in which Bob is selected, etc.

Small spaces are provided on the form, each associated with one of the contest spaces to receive a figure indicating the number of entries selected to win in the corresponding contest. Thus in the form shown 55 in the drawings the small rectangular space 6^a at the bottom of column 4^a is provided in which the numeral 2 is written by the player or by some other person to indicate that 60 two entries in the first column are selected to win. In the similar space 6^b at the bottom of the second contest column the numeral 1 is recorded, since only one contestant is selected in this contest, similar spaces 65 being provided, as indicated in the drawing,

for the other contest columns. Suitable printed words or other indicia are provided in association or alignment with the spaces 6^a and 6^b etc., to indicate the purpose of the spaces, such indicia being indicated in the 70 drawing at 7, where the words "Number of entries in each contest selected to win" are indicated as printed.

At a suitable point on the form such as at the bottom of each portion such as 1^a 75 of the form another small space is provided such as the rectangular space indicated at 8. This space is to receive a figure indicating the total number of combinations of possible winners selected or played by the 80 player, the purpose of this space being indicated by suitable words or indicia such as the words indicated at 9 "Total of combinations."

It will be evident that the total of combinations may be arrived at very quickly by multiplying together the figures in all of the small spaces 6^a, 6^b, etc. In the example given in the drawing the figures referred to 90 multiply together to make eight, as is indicated.

A player having filled out a form, as indicated, the three portions thereof may be torn apart along the perforated lines, the original kept by the player, the copies of the 95 forms made out by the various players being retained by some person as a record of the plays made until after the contests have taken place. In the case of the form illustrated the player will win the game, or be 100 one of the winners, if any one of his eight combinations selected proves to be the correct list of the winners in all of the seven contests. If no player has selected, in any of his combinations, all of the winners in 105 the various contests, the winner of the game will be the player who has selected the greatest number of winners in the various contests.

It will be evident that the form described 110 greatly simplifies the recording of any number of combinations of contestants in the various contests and enables the calculation and recording of the number of combinations selected to be made in an exceedingly 115 simple manner.

It will be understood that the invention is not limited strictly to the details of construction which have been shown, but that the same is as broad as is indicated by the 120 accompanying claims.

It should particularly be noted that, as 125 stated above, the form illustrated takes the place of as many separate sheets as the combinations played, in accordance with the prior procedure. Thus, in the example given, under the old procedure, one sheet would give the names Almoner, Ada M., Mabel, Jack, U. S., France, and Prince, as 130 selections in the seven contests; the second

sheet would contain the names Almoner, Ada M., Mabel, Jack, U. S., Battina and Prince; the third, the names Almoner, Ada M., Mable, Jule, U. S., France, and Prince; the fourth, Almoner, Ada M., Mabel, Jule, U. S., Bettina, and Prince; and the fifth to eighth, respectively, would contain the same names as the first to fourth sheets, respectively, except that the name Bob would appear instead of the name Almoner in each instance.

What I claim is:

1. A combination entry form for contests or games, comprising a sheet provided with delineated contest spaces and means indicating the several contests to which said spaces are respectively devoted, each said space having provision for recording the names of a plurality of selections as possible winners in the contest represented by said space, smaller delineated spaces associated, one with each of said first spaces, each to receive a figure representing the number of the entries selected to win in the one of said first spaces associated therewith, said sheet also having a delineated space to receive a figure representing the number of possible combinations of winners in the various contests from the selections of winners recorded in all of said first spaces.

2. A combination entry form for contests or games, comprising a sheet provided with delineated contest spaces and means indicating the several contests to which said spaces are respectively devoted, each said space having provision for recording the names of a plurality of selections as possible winners in the contest represented by said space, smaller delineated spaces associated with said first spaces, and indicia for indicating that each of the said smaller spaces is to receive a record of the number of entries in the one of said first delineated spaces associated therewith selected to win, said sheet also having a delineated space to receive a figure representing the number of

possible combinations of winners in the various contests from the selections of possible winners recorded in all of said first spaces, and indicia indicating that said space is for recording such total number of combinations.

3. A combination entry form for contests or games, comprising a sheet provided with delineated contest spaces and means indicating the several contests to which said spaces are respectively devoted, each said space having provision for recording the names of a plurality of selections as possible winners in the contest represented by said space, and a comparatively small delineated space to receive a figure representing the number of possible combinations of winners in the various contests from the selections of possible winners recorded in all of said first spaces.

4. A combination entry form for contests or games, comprising a sheet having duplicate portions adapted to be folded one over the other, the under portion being adapted to form a carbon copy of matter written on the upper portion, each portion being provided with delineated contest spaces and means indicating the several contests to which said spaces are respectively devoted, each said space having provision for recording the names of a plurality of selections as possible winners in the contest represented by said space, smaller delineated spaces associated one with each of said first spaces, each to receive a figure representing the number of entries selected to win in the one of said first spaces associated therewith, said portion also having a delineated space to receive a figure representing the number of possible combinations of winners in the various contests from the selections of winners recorded in all of said first spaces.

In testimony whereof I have signed my name to this specification.

ERNESTO D. REYES.
